(57) **CLAIM**

The ornamental design for a protection device for a mobile telephone with automatic opening, as shown and described.

DESCRIPTION

FIG. 1 is a front perspective view of a protection device for a mobile telephone with automatic opening showing my new design, according to a first embodiment of the invention, in a closed configuration;

FIG. 2 is a front elevation view thereof in the closed configuration;

FIG. 3 is a rear elevation view thereof in the closed configuration;

FIG. 4 is a left side elevation view thereof in the closed configuration;

FIG. 5 is a right side elevation view thereof in the closed configuration;

FIG. 6 is a top view thereof in the closed configuration;

FIG. 7 is a bottom view thereof in the closed configuration;

FIG. 8 is a front perspective view thereof in an open configuration;

FIG. 9 is a front elevation view thereof in the open configuration;

FIG. 10 is a front perspective view of a protection device for a mobile telephone with automatic opening showing my new design, according to a second embodiment of the invention, in a closed configuration;

FIG. 11 is a rear perspective view thereof in the closed configuration;

FIG. 12 is a front elevation view thereof in the closed configuration;

FIG. 13 is a rear elevation view thereof in the closed configuration;

FIG. 14 is a left side elevation view thereof in the closed configuration;

FIG. 15 is a right side elevation view thereof in the closed configuration;

FIG. 16 is a top view thereof in the closed configuration;

FIG. 17 is a bottom view thereof in the closed configuration;

FIG. 18 is a front perspective view thereof in an open configuration; and,

FIG. 19 is a front elevation view thereof in the open configuration.

The portions of the protection device for a mobile telephone with automatic opening shown in broken lines form no part of the claimed design.
